J. A. DE VILBISS

SAFE

Filed May 16, 1924

FIG. I

FIG. II

FIG. III

INVENTOR
John A. De Vilbiss
BY Cook & McCauley ATTYS

Patented Aug. 25, 1925.

1,550,887

UNITED STATES PATENT OFFICE.

JOHN A. DE VILBISS, OF ST. LOUIS, MISSOURI, ASSIGNOR TO JOHN V. LEE, OF ST. LOUIS, MISSOURI.

SAFE.

Application filed May 16, 1924. Serial No. 713,657.

To all whom it may concern:

Be it known that I, JOHN A. DE VILBISS, a citizen of the United States of America, a resident of the city of St. Louis, in the State of Missouri, have invented certain new and useful Improvements in Safes, of which the following is a full, clear, and exact description, reference being had to the accompanying drawing, forming a part of this specification.

This invention relates to improvements in safes, and the main object of the invention is to produce a safe which is so constructed as to withstand the attempts of persons to gain access to the interior thereof by blowing the door from said safe by means of an explosive charge.

Briefly stated, my improved safe comprises an outer compartment, a second compartment located within said outer compartment, and a door hinged to said second compartment and adapted to be locked within a doorway formed in a wall of said outer compartment, the contacting faces of said door and doorway being plane instead of stepped as heretofore, thereby eliminating all abutment faces between which a charge of explosive may be exploded to blow the door from the safe.

With the foregoing and other objects in view, the invention comprises the novel construction, combination and arrangement of parts hereinafter more specifically described and illustrated in the accompanying drawings, wherein is shown the preferred embodiment of the invention. However, it is to be understood that the invention comprehends changes, variations and modifications which come within the scope of the claims hereunto appended.

Fig. I is a horizontal section of a safe made in accordance with my invention.

Fig. II is a cross section on line II-II of Fig. I.

Fig. III is a plan view on a reduced scale of my improved safe showing same as it would appear when the inner compartment has been moved outwardly to permit the outer door to be swung to an open position.

In the drawing, A designates my improved safe which comprises an outer compartment B and an inner compartment C. The outer compartment or receptacle B is in

the form of a safe having a top wall 1, a bottom wall 2, side walls 3 and 4, a rear wall 5 and a front wall 6. 7 designates a comparatively thick door which is adapted to lie within a doorway 8 in the front wall of the outer compartment B. The outer compartment B is provided with a plurality of rectangular ribs 9 which extend inwardly from the side, top and bottom walls of said outer compartment, said rectangular ribs being preferably formed integral with said side, top and bottom wall of said outer compartment.

Arranged within the outer compartment B is an elongated shell 10, which as is clearly shown in Fig. II is rectangular in cross section. The side, top and bottom walls of said rectangular shell 10 contact with the inside faces of the rectangular ribs 9 so that said shell 10 is supported by said ribs. The shell 10, as will be observed by referring to Fig. I, is open at its opposite ends.

Located within the elongated shell 10 is the inner compartment C. The compartment C has the same cross sectional shape as the elongated shell 10 and as the outer compartment B. In other words, said inner compartment has an upper, a lower and side walls which are in close contact with the upper, lower and side walls of the elongated shell 10 (Fig. II), and while the walls of said inner compartment are in contact with the walls of said elongated shell, the relative cross sectional dimensions of said parts are such that said inner compartment may be moved longitudinally of said elongated shell. As clearly shown in Fig. I, the comparatively thick door 7 which has been described as being adapted to be moved into the doorway 8 is supported by the inner compartment C, there being hinges 11 whereby said door may swing relative to said inner compartment. Arranged within the inner compartment C is a second door 12, which is hingedly supported by a wall of said inner compartment at a point which is adjacent to the forward end of said inner compartment. The door 12 is of the ordinary type and is provided with any suitable locking mechanism.

The door 7 fits closely within the doorway 8, and said door has plane top and bottom edges and plane side edges. The doorway 8 is likewise provided with plane

door-receiving surfaces surrounding and conforming to said door edges when the door is in a closed position, and as a result of this the thick door 7 cannot swing in an arc of a circle while it is confined in the doorway, but must be moved in a straight line parallel with the plane surfaces. The door 7, as has already been stated, is hingedly supported by the slidable inner compartment C.

10 13 designates locking bolts of a well known type which are carried by the door 7 and are adapted to project from the plane edges thereof as shown by dotted lines in Fig. I, so as to enter the recesses in the plane faces of a doorway 8. 14 designates an operating handle adapted to control the locking bolts through the medium of mechanism not shown, and 15 designates the rotary dial of a combination lock. It is understood, however, that other suitable locking means could be used in connection with the door herein shown.

When the door 7 is closed an explosive 25 charge may be forced between the plane edges of said door and the plane surfaces of the doorway, but when the charge is exploded between these plane faces its explosive force will not tend to destroy the locking bolts 13. Furthermore, the explosion between these 30 plane surfaces of the door and doorway will not tend to force the door outwardly from the doorway as it would if said charge were exploded between abutting faces such as the 35 abutting faces found when the ordinary stepped-edge safe-door is locked in a doorway provided with corresponding steps.

To open the door after it has been unlocked the operating handle is grasped to 40 pull the door 7 and the inner compartment C associated therewith outwardly in a straight line, thereby locating the door and its hinges 11 in the positions in which they are shown in full lines in Fig. III. To completely open the door 7 the same operating 45 member 14 is used to swing the door on its hinges to the position shown in dotted lines in Fig. III. When the door 7 is closed the hinges 11 lie within the safe, but after the 50 door has been pulled to the position shown by full lines in Fig. III the hinges 11 are outside of the safe and at the corner of the doorway.

Arranged between the rear wall 5 of the 55 outer compartment B and the rear wall of the inner compartment C is a pair of coil springs 16. The coil springs 16 are of such length that when the inner compartment is in its rearmost position and the door 7 locked in the doorway 8, said springs are under compression, consequently when the locking bolts 13 are withdrawn from the recesses in the walls of the door opening 8 said coil springs will exert a forward pressure 60 against the inner compartment C,

thereby rendering it possible to draw said inner compartment C outwardly from the outer compartment with very little effort.

To increase the ability of my improved safe to withstand fire and heat, I provide 70 the outer compartment thereof with a lining of a suitable insulating material, as indicated by the reference character 17 in Fig. I.

In manufacturing my improved safe I 75 prefer that the outer compartment B and the door 7 be formed of a very hard material, such as manganese steel, but because they are located within said outer compartment and are thus protected thereby it will 80 not be necessary to form the inner compartment C or the rectangular shell 10 of as hard a material as the outer compartment, but on the other hand, they may be formed of a less expensive material whereby the 85 cost of producing the safe is reduced.

I claim:

1. A safe comprising an outer compartment having a doorway, an inner compartment within said outer compartment and 90 movable through said doorway, and a door supported by said inner compartment and adapted to close said doorway of said outer compartment.

2. A safe comprising an outer compartment having a doorway, an inner compartment within said outer compartment and movable therein, and a door supported by said inner compartment and adapted to close said doorway of said outer compartment, 100 the edges of said door and the door-receiving faces of said doorway being plane and said door being movable in a straight line into and out of said doorway.

3. A safe comprising an outer compartment having a doorway, inwardly extending ribs formed on the walls of said outer compartment, an inner compartment within said outer compartment and movable therein, 110 said inner compartment being supported by said inwardly extending ribs, and a door hingedly supported by said inner compartment and adapted to close said doorway of said outer compartment.

4. A safe comprising an outer compartment having a doorway, inwardly extending ribs formed on the walls of said outer compartment, an inner compartment within said outer compartment and movable therein, 115 said inner compartment being supported by said inwardly extending ribs, and a door hingedly supported by said inner compartment and adapted to close said doorway of said outer compartment, the edges of said door and the door-receiving faces of said doorway being plane and said door being movable in a straight line into and out of said doorway.

5. A safe comprising an outer compartment having a doorway, an inner compartment 130

- ment within said outer compartment and movable therein, a door hingedly supported by said inner compartment and adapted to close the doorway of said outer compartment, the walls of said outer compartment and the walls of said inner compartment being spaced apart from each other, and insulating material located in the spaces between the walls of said compartments. 5
- 10 6. A safe comprising an outer compartment having a doorway, an inner compartment within said outer compartment and movable therein, the walls of said inner compartment being spaced apart from the 15 walls of said outer compartment, a door hingedly supported by said inner compartment and adapted to close the doorway of said outer compartment, integral ribs extending inwardly from the walls of said outer compartment, and insulating material located in the spaces between the walls of 20 said compartments and between said inwardly extending ribs.
- 25 7. A safe comprising an outer compartment having a doorway, an inner compartment within said outer compartment and movable therein, a door hingedly supported by said inner compartment and adapted to close the doorway of said outer compartment, and means tending to move said inner compartment outwardly when it is in its 30 rearmost position.
8. A safe comprising an outer compartment having a doorway, an inner compartment within said outer compartment and movable therein, a door hingedly supported by said inner compartment and adapted to close the doorway of said outer compartment, and means comprising a coil spring tending to move said inner compartment outwardly when it is in its rearmost position. 35
9. A safe comprising an outer compartment having a doorway, an inner compartment within said outer compartment and movable therein, the walls of said inner compartment being spaced apart from the walls of said outer compartment, a door hingedly supported by said inner compartment and adapted to close the doorway of said outer compartment, a second door hingedly supported by said inner compartment and adapted to close an end thereof, integral ribs extending inwardly from the walls of said outer compartment, a shell supported by said ribs, and insulating material located in the spaces between the walls of said outer compartment and the walls of said shell and between said ribs, the edges of said door and the door-receiving faces of said doorway being plane and said door being movable in a straight line into and out of said doorway. 40
